UNITED STATES PATENT OFFICE.

PAUL E. COLLINS, OF BOSTON, MASSACHUSETTS.

CIRCUIT-CONTROLLING APPARATUS.

1,101,254.

Specification of Letters Patent. Patented June 23, 1914.

Application filed May 11, 1907. Serial No. 373,155.

To all whom it may concern:

Be it known that I, PAUL E. COLLINS, of Boston, county of Suffolk, and State of Massachusetts, have invented an Improvement in Circuit-Controlling Apparatus, of which the following description, in connection with the accompanying drawings, is a specification, like letters on the drawings representing like parts.

This invention relates to a circuit controlling device especially adapted among other uses, to be employed for controlling the circuits of incandescent lamps used to illuminate signs, pictures and the like.

Provision is made for lighting a plurality of sets of lamps in an alternate manner, and for controlling the length of time each set of lamps is lighted. For this purpose I employ a circuit controller for the lamp circuits, which is moved in one direction when an electro-magnet is energized, and is moved in the opposite direction when the electro-magnet is deenergized. The electromagnet is governed by a circuit controller which is moved in one direction when the electromagnet is energized and is moved in the opposite direction by a weight which is controlled by a pneumatic device as will be described.

These and other features of this invention will be pointed out in the claims at the end of this specification.

Figure 1 is an elevation of an apparatus embodying this invention, showing also a diagram of lamp circuits. Fig. 2, an elevation of the apparatus shown in Fig. 1 in a different position from that shown in said figure; Fig. 3, a plan view of the apparatus shown in Fig. 1. Fig. 4, a detail to be referred to, Fig. 5, a detail in section, taken on the line 5—5 Fig. 4 and looking upward. Fig. 6, a detail of the magnet circuit controller and its operating cylinder, with the parts in their lowered position, and Fig. 7, an underside view of the lamp circuit controller, looking up in Fig. 3. Fig. 8, a detail in perspective of the main switch.

Referring to Fig. 1, *a* represents one set of incandescent lamps and *b* a second set, which may be used to illuminate the opposite sides of a sign or other device (not shown). The lamps *a*, *b* are designed to be alternately lighted, that is, when the lamps *a* are lighted, the lamps *b* are not lighted, and vice versa. The lamps *a*, *b* are controlled by a circuit controller comprising as hereinshown terminal plates *c*, *d*, sepa-

rated by insulation *e* and provided with metal strips forming channels or pathways for the passage of the movable member *f* of the circuit controller. In the present instance, the terminal plate *c* has projecting from it metal pieces *h*, *i*, which form a path or way *j*, and the terminal plate *d* has projecting from it metal pieces *k*, *m*, forming a path or way *n*. The metal pieces *h*, *n* may be secured at one end and left free at the opposite end, and may and preferably will have secured to them spring pieces or brushes *o*, *p*, which extend across the pathways *j*, *n* and normally engage the metal pieces *i*, *k*. The movable member *f* of the lamp circuit controller is shown as a finger attached to the lower end of a spring arm *s*, fastened to a metal piece 10 secured to but insulated from a lever 12, which is mounted on a pivot stud 13 extended from a suitable back plate or support 14. The lever 12 is turned on its pivot in one direction to raise the movable member *f* of the circuit controller, by an electromagnet 15, herein shown as a solenoid, whose core 16 is connected by a link 17 to the lever 12, and said lever is moved in the opposite direction to lower the movable member of the circuit controller by a weight 18, which is represented as secured to a rod 19 extended from said lever on the opposite side of the pivot to the solenoid. The movement of the lever 12 by the solenoid may be limited by a back stop, shown as a bent rod or arm 109 attached to the plate 14.

Provision is made for energizing and de-energizing the solenoid, and for this purpose, I have provided a circuit controller for said solenoid. The solenoid circuit controller may be made as herein shown and comprises a metal arm 20 provided at its end with a finger 21, which coöperates with a terminal plate 22, shown separately in Figs. 4, 5 and 6, and which is provided with a spring piece 23 and with two rigid pieces 24, 25 forming a path or way 26 through which the finger 21 passes on its downward movement and onto a block of insulation 27 secured to the plate 22, the said block having a wall 28, which extends substantially at right angles to it for a purpose as will be described. The spring piece 23 coöperates with the wall 28 and metal piece 24 to form a pathway 29 for the contact finger 21 on the upward movement of the latter. The movable member of the magnet circuit controller, is moved in one direction by the lever

12, and in the opposite direction by gravity, and its movement by gravity is regulated by means of a pneumatic device, comprising as hereinshown, an air-containing cylinder 30, provided with a piston or plunger 31 having a hollow stem 32 provided at or near its lower end with an air outlet 33. The cylinder 30 has attached to its upper end a guide rod 35, which moves in a guide block 36 attached to a stationary part or piece 37.

10 Provision is made for lifting the cylinder by the lever 12, and for releasing said cylinder when it has been lifted a predetermined distance. This may be accomplished as hereinshown by a latch 40 depending from the lever 12 and adapted to be engaged by a pawl 41 pivoted to the cylinder at 42 and having an arm 43, which is adapted to engage a stationary device or arm 44, secured in the present instance to the guide block 36. The lever arm 43 is acted upon by a spring 46 to normally throw the pawl 41 into position to be engaged by the latch 40, (see Fig. 1).

25 The cylinder 30 may have secured to it a weight 47, which also serves as a guide for the cylinder and moves on a stationary guide rod 49 attached to the guide block and to a stationary block 51. The piston rod 32 is stationary and for this purpose engages a cross piece 50 attached to the stationary block 51. The cylinder 30 may have attached to it a stop arm 52, which engages the cross piece 50 and limits the downward movement of the cylinder.

40 The air cylinder may be open at its lower end and the piston 31 may be of a construction, similar to a bicycle pump, to permit air to be drawn around the piston into the cylinder on the upward movement of the latter and to prevent its escape around the piston on the downward movement of the said cylinder, thereby causing the air to pass out through the hollow piston rod and the outlet port 33, which latter can be made of such size as to regulate the time it takes the air to escape and consequently the cylinder 30 to descend, thereby regulating the time it takes the movable member 20 of the circuit controller for the magnet to travel downward.

45 The movable member 20 of the magnet circuit controller is connected in circuit with the electromagnet or solenoid 15 as is also the terminal 22, and said movable member is preferably insulated from the air cylinder, and for this latter purpose, the member 20 is secured to an arm 55, which is insulated from the cylinder 30 by an insulator 56. The movable member *s* of the light circuit controller is also preferably insulated from the lever 12 by the insulation 58 and by a second insulator 59 mounted on the pivot 13 (see Fig. 2) and having mounted on it a metal sleeve 60 which is connected by wire

61 to the terminal block 10, said sleeve being engaged by a brush 62, which is attached to a binding post or terminal 63.

The lamps *a*, *b*, are supplied with current from the main line 64, 65, provided with a switch of ordinary construction, such as a plug switch, but which is represented as a lever switch, having blades 66, 67, which cooperate with terminals 68, 69. The terminal 68 is connected by wire 70 to the binding post or terminal 63, which is connected to the member 20 of the magnet circuit controller by wire 71. The terminal plate 22 is connected by wire 72 to a fuse 73 of ordinary construction, and the latter by wire 74 to one end of the coil of the solenoid, the other end of which is connected by wire 75 to the fuse 76, which is connected by wire 77 to the terminal 69. The terminal plates *c*, *d* for the lamp circuit controller have connected to them the wires 80, 81, which include the two sets of lamps *a*, *b*, and the common return wire 82 for the lamp circuits is connected with the terminal 69.

50 The operation of the apparatus may be briefly described as follows:—As represented in Fig. 1, both sets of lamps are out as the main switch is opened; the cylinder 30 is in its lowered position and clutched to the lever 12, which is turned into the position shown, by the weight 18; the contact finger *f* engages the spring *p*, and the contact finger 21 engages the spring 23. If the line switch is now closed, the circuit of the solenoid 15 is closed, as is also the circuit 100 of the set *b* of lamps. The solenoid circuit may be traced as follows:—from the positive line wire 64 by switch blade 66 to terminal 68, thence by wire 70 to binding post 63, wire 71, contact arm 20, finger 21, spring 105 23, terminal 22, wire 72, fuse 73, wire 74, through the solenoid 15, thence by wire 75, fuse 76, wire 77, negative terminal 69, switch blade 67, to negative wire 65. The circuit of the lamps *b* may be traced as follows:—110 from the positive terminal 68 to the binding post 63 as above, thence by brush 62, sleeve 60, wire 61, terminal block 10, contact arm *s*, finger *f*, terminal *d*, wire 81, lamps *b* and wire 82 to negative terminal 69. 115 The solenoid attracts its core 16 and turns the lever 12 from the position shown in Fig. 1 to that shown in Fig. 2. The lever 12 on what may be termed its upward movement, lifts the cylinder 30, the contact arm 20, and 120 the contact arm *s*. At or about the time the lever 12 has reached the end of its upward movement, the finger *f* on the contact arm *s* passes from engagement with the terminal *d* across the insulation *e* into engagement 125 with the terminal *c*, thereby opening the circuit of the lamps *b* and establishing the circuit of the lamps *a*.

125 At or about the same time, the contact finger 21 has been brought beyond the end 130

6 of the piece 24 and passes across the plate 22 into engagement with the metal strip 25 and into position to be moved down in the path 26 and the clutch lever 41 is at this 5 time disengaged from the latch 40 by the arm 43 of said lever engaging the stationary arm 44. The cylinder 30 is thus released, and begins to descend, being governed by the size of the outlet port 33 in the 10 piston rod, which port is made of such size as to cause a given length of time to be consumed in the descent of the cylinder, thereby permitting the circuit of the lamps *a* to remain closed and the lamps lighted a given 15 or predetermined length of time, or until the contact arm *s* is moved down through the path *j* and beyond the metal piece *i*, whereupon the contact arm *s* springs across the insulation *e* and into engagement with the spring *p* as represented in Fig. 1.

The downward movement of the contact arm *s* is effected by the downward movement of the lever 12 under the influence of the weight 18 and this movement of the 25 lever 12 takes place when the circuit of the magnet 15 is opened, which occurs when the contact arm 20 is carried by the descending cylinder 30 out of engagement with the terminal piece 22 and into engagement with the insulation 27, 28. The magnet 15 remains deenergized while the finger 21 of the contact arm 20 remains in engagement with the insulating wall 28, thereby allowing the cylinder 30 to complete its downward movement, and at or about the time 35 the cylinder 30 has completed its downward movement, the finger 21 on the contact arm 20 passes out of engagement with the insulating wall 28 and snaps into engagement with the spring 23 on the terminal piece 22, (see Fig. 6) thereby again closing the circuit of the magnet 15. The contact arm *s* remains in engagement with the spring *p* on the terminal *d* and the lamps *b* remain 40 lighted until the magnet 15 is energized and the contact arm *s* is again brought into engagement with the terminal *c* as shown in Fig. 2. It will thus be seen, that the set of lamps are alternately lighted, and remain 45 lighted a given or predetermined length of time, which is controlled by the pneumatic governor or cylinder.

To reduce vibration of the free ends of the springs *m*, *h*, and thereby avoid arcing between the contact finger *f* and the said springs, the free ends of said springs have attached to them one end of coiled springs 55 90, 91, the other ends of which bear on the terminal plates *d*, *c*, and serve as steadyng devices for the springs *m*, *h*. In the construction of the circuit controller for the lamps *a*, *b*, the contact finger *f* on its upward movement slides along the spring *p* until it reaches the plate *k*, along which it 60 slides until it reaches the end of said plate,

whereupon it slips off into contact with the spring *o*. On the downward movement of the finger *f*, it slides along the spring *o* until it reaches the plate *i*, along which it slides to the end of said plate, from which 70 it slips into contact with the spring *p*.

Claims:

1. In a device of the character described, in combination, a plurality of sets of electric lamps, circuits in which said lamps are included, a circuit controller for said lamp circuits comprising circuit terminals and a movable member coöperating therewith, a lever to which said movable member is connected to move therewith, a solenoid to move 75 said lever in one direction, means to move said lever in the opposite direction, a circuit controller for said solenoid comprising a terminal and a movable member, a pneumatic device to regulate the movement of 80 the movable member of the solenoid circuit controller and comprising a stationary piston and a movable cylinder to which the movable member of said solenoid circuit controller is connected to move therewith, a clutch to couple the said cylinder to said lever, and means to disengage said clutch and release said cylinder from said lever and permit it to move independently of said lever, substantially as described. 85

2. In a device of the character described, in combination, a circuit controller, a lever to which said circuit controller is connected, an electromagnet to move said lever, a separate circuit controller for said electromagnet, a movable cylinder to which the circuit controller for said electromagnet is connected to move therewith, a clutch to couple 100 said cylinder to said lever to effect movement of said cylinder and the magnet circuit controller in one direction, and means to disengage said clutch from said lever and permit it to move independently of said lever, substantially as described. 105

3. In a device of the character described, in combination, an electric circuit, a circuit controller therefor, mechanism to mechanically move said circuit controller, an electromagnet governing the operation of said mechanism, a switch to open and close the 110 circuit of said electromagnet, means to couple the said magnet circuit controller with said mechanism to effect movement of the said switch in one direction by said mechanism, means to release said switch from said 115 mechanism and permit the said magnet circuit controller to move independently of said mechanism, and means to regulate the movement of said switch when released from said mechanism, substantially as described. 120

4. In a device of the character described, in combination, an electric circuit, a circuit controller therefor, mechanism to mechanically move said circuit controller, an electromagnet governing the operation of said 125 130

mechanism, a switch to open and close the circuit of said electromagnet, means to couple the said switch with said mechanism to effect movement of the said switch in one direction by said mechanism, means to release said switch from said mechanism, a movable cylinder to which said switch is connected to move therewith, a stationary piston in said cylinder, and means to regulate the escape of fluid from said cylinder when the latter is moved in one direction, substantially as described.

5. In a device of the character described, in combination, an electric circuit, a circuit controller therefor, mechanism to mechanically move said circuit controller, an electromagnet governing the operation of said mechanism, a switch to open and close the

circuit of said electromagnet, means to couple the said switch with said mechanism to effect movement of the said switch in one direction by said mechanism, means to release said switch from said mechanism, a movable cylinder to which the switch is connected to move therewith, a stationary piston within said cylinder having a hollow stem communicating with the said cylinder and having a fluid outlet, substantially as described.

In testimony whereof, I have signed my name to this specification in the presence of two subscribing witnesses.

PAUL E. COLLINS.
